UNITED STATES PATENT OFFICE.

JOSEPH BERGER, JR., OF UTICA, NEW YORK, ASSIGNOR TO UNION SPECIAL MACHINE COMPANY, OF CHICAGO, ILLINOIS, A CORPORATION OF ILLINOIS.

TAPE-GUIDE FOR SEWING-MACHINES.

1,195,767.

Specification of Letters Patent. Patented Aug. 22, 1916.

Application filed September 18, 1912. Serial No. 721,048.

To all whom it may concern:

Be it known that I, JOSEPH BERGER, Jr., a citizen of the United States, residing at 40 Genesee street, Utica, in the county of 5 Oneida, State of New York, have invented certain new and useful Improvements in Tape-Guides for Sewing-Machines, of which the following is a description, reference being had to the accompanying drawing 10 and to the figures of reference marked thereon.

The invention relates to new and useful improvements in tape guides for sewing machines.

15 An object of the invention is to provide a tape guide which is so supported that it may be readily moved away from the stitching mechanism to facilitate the cutting of the tape, and which is further so constructed that it may be moved for feeding or placing the cut end of the tape underneath the presser foot, whereby said tape will be engaged and moved forward by the feeding mechanism without requiring any 20 hand manipulation of the tape.

A further object of the invention is to provide a tape guide and support therefor with means for moving the tape guide to feed or place the tape underneath the presser 30 foot, which means is actuated from a treadle or knee shift, so that the operator's hands may be free to shift or manipulate the material being stitched.

35 A further object of the invention is to provide a tape guide and supporting mechanism of the above character which is so constructed that the tape guide will be automatically moved upon the raising of the presser foot to its extreme upper limit, so 40 that the free end or cut end of the tape may be inserted or placed underneath the presser foot.

These and other objects will in part be obvious, and will in part be hereinafter more 45 fully described.

In the drawings, which show by way of illustration one embodiment of the invention. Figure 1 is a rear view of a sewing machine, having my improvement applied thereto; Fig. 2 is an enlarged perspective view showing a portion of the sewing head and my improved tape guide attached thereto; Fig. 3 is a view similar to Fig. 2, showing the tape guide raised to permit the cutting of the tape; Fig. 4 is a detail partly 55 in section and partly in end view showing the support for the tape guide and its attachment to head of the machine. Fig. 5 is a detail in plan showing one of the purposes for which my improved guide may be 60 used.

In the drawings I have shown my improved tape guide as applied to a sewing machine consisting of a work support 1, an overhanging arm 2, a needle bar 3, carrying spaced needles 4. Coöperating with the needles beneath the work support may be any suitable complementary stitch forming mechanism. The needle bar is reciprocated in the overhanging arm by the usual needle 70 lever, which is operated from the main shaft 5 by an eccentric strap or link 6. Also mounted in the overhanging arm is a presser bar 7, carrying a presser foot 8, at its lower end. This presser bar 7 is provided with a 75 collar 9, which carries a pin 10, and the leaf spring 11, resting on the pin normally holds the presser bar in yielding engagement with the work support. The presser foot is raised by a lever 12, which is pivoted at 13 80 to the overhanging arm. The rear end of the lever 12 is provided with a chain or other flexible member 14, which is connected to a treadle or knee shift. This lever 12 is held depressed at its forward end by a 85 spring 15. Upon depressing the treadle or moving the knee shift laterally, the lever 12 will be oscillated about its pivotal support and the free end of the lever will engage the pin 10 and raise the presser foot 90 from the work support.

Mounted to reciprocate vertically in lugs carried by the overhanging arm is a guide bar 16. This guide bar is provided with a collar 17 and with a laterally projecting arm 95 or pin 18 which extends through the presser bar 7. This guide bar 16 will, therefore, be raised and lowered with the presser bar, and will prevent the presser bar from rotating in its bearings. At the lower end of the 100 guide bar 16 is a laterally projecting block or bracket 19. Pivoted to this bracket 19 is an arm 20, a pin or screw 21 extends through the arm into the bracket 19 and serves as a pivotal support for the arm. A 105 flexible washer or tension plate 22 is carried by the pivot pin 21, and bears against the arm 20, so that said arm will be fric-

tionally held against the supporting bracket 19 therefor. This arm 20 projects forwardly and is bent laterally in front of the needle bar, and the tape guide 23 is carried thereby. 5 This tape guide, as herein shown, is rectangular in cross section, thus forming a front wall 24 and a rear wall 25. A spring 26 is attached to the head of the tape guide by a screw 27. This spring projects upwardly and is curved so as to extend downwardly through the tape guide. The purpose of the spring is to put a slight tension on the tape, which may be changed by turning the screw 27. The spring 26 rests on 10 the inner end of the screw 27, so that by turning the screw 27 the spring may be forced toward the inner wall 24 of the tape guide. This causes the spring to press against the tape and put a tension thereon, 15 so as to prevent the tape from being drawn back through the tape guide.

A pin 28 carried by the arm 20 engages the bracket 19 and limits the downward movement of the arm 20. When the arm 20 25 is lowered so that the pin engages the bracket, the tape guide is so proportioned that the delivering end is below the upper face of the presser foot and adjacent the under surface of said presser foot. The 30 presser foot 8, as shown in the drawings, is cut away, as at 29, to make room for the tape guide.

Mounted on the head of the machine is an adjustable stop 30. This stop is in the 35 form of a laterally projecting lug, having a tapering face 31 on its lower edge. The arm 20 is formed with a V-shaped notch, which provides two inclined walls 32 and 33.

In the operation of my device the tape 40 guide is positioned as shown in Fig. 2, and the tape T passing through the guide will be laid underneath the presser foot so that the edges of the tape will be stitched to the body material by the needles 4—4. When it 45 is desired to end the tape on a garment, the arm 20 is swung about its pivotal point and the stop 30 will engage the wall 32 on said arm 20 and limit the upward movement of the tape guide. In Fig. 3 of the drawings 50 I have shown the tape guide swung to this position, and in dotted line I have shown the manner of the severing of the tape. By this moving of the tape guide away from the stitching mechanism, the tape may be severed so that the end thereof can be folded 55 underneath for finishing off the tape. When the parts are in this position, shown in Fig. 3, the lower edge of the stop 30 is some distance above the wall 33, so that the 60 presser foot may be raised sufficiently for removing the material, if desired, before the stop contacts with the wall 33. A further lifting of the presser foot, which carries with it the bracket supporting the tape 65 guide, will cause the inclined wall 33 to slide

along the stop 30 and thus force the arm 20 to its lower position where the stop 28 engages the bracket 19. This downward movement of the arm 20 carries the tape guide to its normal position relative to the presser foot, and the free or cut end of the tape projecting beyond the end of the tape guide will be inserted or placed underneath the presser foot so that when the presser foot is lowered, and the machine started, the tape 75 will be automatically engaged by the said feed and carried to the stitching mechanism without requiring any hand manipulations of the tape. Inasmuch as the presser foot is raised and lowered by the treadle or knee 80 shift connection, it will be apparent that the tape may be inserted under the presser foot and carried to the stitching mechanism through the control of the presser foot by this treadle or knee shift, thus leaving the 85 hands of the operator free to manipulate the material being stitched. This is of special advantage in doing such classes of work as stitching and covering the opening made in the front of a lady's vest, as shown for 90 example in Fig. 5. The inserted material 34 is stitched to the body garment 35 and a tape 36 applied, so as to cover the cut edge of the inserted part 34. When the turning point 95 is reached, the presser foot may be raised without disturbing the relative position of the tape guide so that the goods may be readily manipulated for stitching the opposite side of the insertion. When the end of the seam is reached, the tape guide may be 100 raised and the tape severed, as above noted, so that the end of the tape may be folded underneath for stitching.

While my improved device is especially adapted for this particular class of work, it 105 is also equally adapted for other types of work, such as stitching labels on garments, where the label is printed on a strip of tape, and for any other class of work where the tape or a strip of fabric is stitched to 110 a garment.

While I have referred to my device as guiding a tape, it is to be understood that I do not limit myself to the guiding of a strip having a selvage edge, but said device may 115 be equally used for guiding a cut strip of fabric.

It is obvious that minor changes in the details of construction and the arrangement of parts may be made without departing 120 from the spirit of the invention as set forth in the appended claims.

Having thus described my invention, what I desire to claim by Letters Patent is:—

1. The combination of a presser foot, a 125 tape guide having means for guiding a tape on to the upper face of the fabric, means for preventing the tape from being withdrawn backward through the guide, means for supporting said guide, and means for moving 130

- the guide for placing the end of the tape carried by said guide underneath the presser foot.
2. The combination of a presser foot, a tape guide having means for guiding a tape on to the upper face of the fabric, means for preventing the tape from being withdrawn backward through the guide, means for supporting said tape guide from the head of the machine, and means for moving said tape guide for inserting the end of the tape carried thereby underneath the presser foot.
3. The combination of a presser foot, a tape guide, means for placing a tension on the tape passing through said guide, means for supporting said tape guide from the head of the machine, means whereby said guide may be moved away from the presser foot, and means for moving said guide toward the presser foot to insert the tape underneath the presser foot.
4. The combination of a presser foot, a tape guide, an arm carrying said tape guide, means for pivotally connecting said arm to the head of the machine, a friction device for holding the arm in adjusted positions, a tension device carried by said guide, a stop for limiting the movement of said tape guide away from the presser foot, and a stop for positioning said tape guide relative to said presser foot.
5. The combination of a presser foot, a tape guide, located directly in front of the stitching mechanism, a tension device for the tape carried thereby, an arm pivoted to the head of the machine so as to move in a vertical plane and carrying said tape guide, a friction washer for holding the arm in adjusted positions, a stop for limiting the upward movement of the arm, and a stop for limiting the downward movement of the arm to position the tape guide relative to the presser foot.
6. The combination of a presser foot, a presser bar, carrying said foot, a tape guide, a support for said tape guide, movable up and down with said presser foot, means whereby said tape guide may be moved independently of said presser foot, and means for moving said guide toward the presser foot and inserting the tape underneath said foot.
7. The combination of a presser foot, a presser bar carrying said foot, a tape guide located in front of the presser foot, an arm carrying said tape guide, means for pivoting said arm, whereby it moves vertically with the presser foot and independent of the presser foot, and means for swinging said arm to position the end of the tape underneath the presser foot, when said presser foot is raised.
8. The combination of a presser foot, means for raising and lowering said foot, a tape guide, and means for lowering said tape guide when the presser foot is raised, whereby the end of the tape is inserted underneath the presser foot.
9. The combination of a presser foot, means for raising and lowering the presser foot, a tape guide movable up and down with the presser foot, and having a movement independent of the presser foot, and devices whereby an extreme upward movement of the presser foot will move said tape guide downward relative to the presser foot for inserting the end of the tape carried thereby underneath the presser foot.
10. The combination of a presser foot, a presser bar supporting said foot, a bracket movable with said presser bar, a tape guide, an arm pivoted to said bracket and carrying said tape guide, a friction device for holding the arm in adjusted positions, a stop carried by said bracket for limiting the downward movement of the arm, a stop for limiting the upward movement of the arm relative to the presser foot, said stop being constructed so as to permit a limited movement of the arm and presser foot, when said arm is raised and whereby an extreme upward movement of the presser foot will move said arm downward to place the end of the tape carried by the tape guide underneath the presser foot.
11. The combination of a presser foot, a presser bar supporting said foot, a bracket movable with said presser bar, a tape guide, an arm pivoted to said bracket and carrying said tape guide, a friction device for holding the arm in adjusted positions, a stop carried by said bracket for limiting the downward movement of the arm, a stop for limiting the upward movement of the arm relative to the presser foot, said stop being constructed so as to permit a limited movement of the arm and presser foot, when said arm is raised and whereby an extreme upward movement of the presser foot will move said arm downward to place the end of the tape carried by the tape guide underneath the presser foot, said tape guide having a tension device bearing on the tape, and means for adjusting said tension device.
12. The combination with a presser foot, means for raising and lowering said presser foot, of a tape-guiding device, means whereby said tape-guiding device is raised and lowered with the presser foot, and means whereby the raising of the presser foot causes the tape guide to be lowered in advance of the lowering of the presser foot.
13. The combination of a presser foot, means for raising and lowering said presser foot from and into operative position relative to the fabric, a tape-guiding device, and means whereby said tape-guiding device is automatically moved into operative position.

position with respect to the presser foot in advance of the return of the presser foot to operative position.

14. The combination of a presser foot, 5 manually-operated means for raising said presser foot, a tape-guiding device, and means for automatically lowering said tape-guiding device when said presser foot is raised for inserting the tape beneath the 10 presser foot.

15. The combination of a presser foot, means for raising and lowering the presser foot, a tape-guiding device having means whereby said tape-guiding device is moved 15 vertically with the vertical movement of the presser foot, and means for moving said tape-guiding device downward in advance

of the presser foot before said presser foot reaches its extreme downward movement.

16. The combination of a presser foot 20 having a tape-guiding recess at the front end thereof, means for raising said presser foot, a tape-guiding device, means for pivotally supporting said tape-guiding device, means whereby said tape-guiding device 25 may be raised, and means for lowering said guide, said recess serving to receive the end of the tape when said guide is lowered.

In testimony whereof, I affix my signature in the presence of two witnesses.
